(57) **CLAIM**

The ornamental design for an extractor unit, as shown and described.

DESCRIPTION

FIG. 1 is a top, front, left side perspective view of an extractor unit showing my design;

FIG. 2 is a front elevation view.

FIG. 3 is rear elevation view thereof.

FIG. 4 is a right side elevation view thereof.

FIG. 5 is a left side elevation view thereof.

FIG. 6 is a top plan view thereof; and,

FIG. 7 is a bottom plan view thereof.

The broken line disclosure represents portions of the extractor unit which form no part of the claimed design.
